SELF-OPENING AND SELF-CLOSING DISPENSER

William S. Berry, P.O. Box 205, Anchorage, Ky.

Filed Mar. 11, 1958, Ser. No. 720,650

1 Claim. (Cl. 222—92)

The present invention relates to dispensers which are self-opening and self-closing whereby paste-like or semi-solid materials may be dispensed at will without the necessity of first opening the dispenser as by unscrewing a protective cap or closure and without the necessity of closing the dispenser after use to protect the contents of the dispenser from deteriorating or being otherwise deleteriously effected by the atmosphere, e.g., by drying to become unduly rigid.

The invention particularly relates to flexible dispensers and even more particularly to dispensers which comprise a container constituted by thin metal walls which are sufficiently flexible to permit squeezing of the container and which are not resilient (accepts a dead fold) so that the container is always filled with paste and becomes progressively smaller as the container is emptied.

The invention especially relates to metal tubular containers such as are commonly used for tooth paste but which tubes are also used in commerce to package various pastes and creams such as hair creams, jellied detergents, oil paints, pigment pastes, suntan lotion, medicinal creams, etc. As is well known, these conventional metal tubular containers are constituted by a cylindrical tube closed at one end by a threaded cap receiving member and, at the other end by the folding and crimping of the cylindrical tube, this folding and crimping being normally accomplished after the tube is filled. As is known, the cap must be removed before the tube can be squeezed to dispense paste therefrom. After use, the cap must be replaced or the contents of the tube adjacent the cap receiving opening will become hardened or spoiled. This removal and replacement of the cap is a nuisance. Further, the cap is small and is frequently misplaced or lost. The invention by eliminating the need for a cap provides a substantial advance in the art.

It will be understood that the cap may be removably secured by friction or other means instead of by the threaded attachment which has been referred to above to provide an illustration of the prior art deficiency.

In accordance with the invention, a dispenser comprising a flexible container is provided with an outwardly flaring generally circular discharge opening within which is seated a conical plug. Resilient means secured to the interior of the container at a point on the container approximately opposite the discharge opening therein is fastened to the plug in a manner effecting a pull on the small end of the conical plug toward the discharge opening. When the flexible container is squeezed or otherwise distorted, the plug is moved away from its seat in the discharge opening against the tension of the resilient means by the pressure applied to the paste so that paste is dispensed through the annular space between the plug and the seat formed by said plug movement. When squeezing is discontinued the resilient means automatically returns the closing plug to its seat so that dispensing is simply a matter of squeeze and release it

2

being unnecessary to have a cap or other permanently separable closing member.

The invention will now be more fully described, reference being had to the accompanying drawings in which the invention is illustrated in connection with a preferred embodiment thereof.

Fig. 1 is a longitudinal cross-section taken through an illustrative tooth paste tube;

Fig. 2 is a partial perspective view of the internally positioned resilient member which, in the form illustrated is strip of rubber;

Fig. 3 is a partial sectional view illustrating the expression of paste upon application of squeezing force to the body of the flexible tube and, the self-opening action of the invention;

Fig. 4 is a view similar to Fig. 3 illustrating the release of squeezing pressure and the self-closing action of the invention;

Fig. 5 is a side elevation of the closing plug;

Fig. 6 is a rear view of the closing plug; and

Fig. 7 is a partial sectional view of the discharge portion of the tube showing a preferred construction in which guide fingers are employed to facilitate proper alignment of the closing plug.

Referring to Fig. 1, the numeral 10 designates a conventional tubular tooth paste tube having a cylindrical body 11 made of metal. The forward end of the tooth paste tube terminates in a portion designated the forward closure 12 having a discharge opening 13 at its forward end. The discharge opening 13 is formed with a plug-receiving seat 14 which is preferably circular and tapers outwardly to enable a good seal to be obtained with the exterior surface of an outwardly tapering conical plug 15. The plug 15 tapers outwardly in a forward direction so that the forward end 16 is larger in diameter than the trailing end 17.

Secured to the plug 15 is a resilient member 18 which is preferably constituted by a strip of elastic material such as rubber. Other resilient means can be used such as a coiled spring. The rubber strip 18 is under tension and extends rearwardly from the plug through the body of the tube 10 and is secured to the tube 10 at a point generally opposite to the discharge opening 13 thereof. The point of securement is at the rear of the tube 10 which, in the form illustrated is constituted by clamping the trailing end of the rubber strip 18 in the folded and crimped rear end of the tooth paste tube identified by numeral 19.

The folding and crimping operations, as is conventional, are preferred after filling the tube 10 with paste, designated 20.

The rubber strip 18 is shown in Fig. 2 and comprises an elongated body 21 and an enlarged forward head 22 which is employed to form preferred securement with the plug 15 as will later more fully appear.

In Fig. 3, a squeezing force illustrated by arrows 23 is being applied to the body 11 of the tube 10. This squeezing force is transmitted to the paste 20 which acts upon the plug 15 to move plug 15 forwardly away from the seat 14 to open an annular space 24 between the exterior conical surface of plug 15 and the seat 14. The squeezing pressure then expels a cylinder of paste identified by numeral 25 through the annular space 24. The shape of paste cylinder 25 will vary with the rigidity of the paste itself and it may partially or completely close as illustrated in Fig. 3 to form a ribbon of paste.

When squeezing pressure 23 is released or discontinued, the metal tube remains partly collapsed and the pressure in paste 20 is relieved by removal of paste through the annular space 24. With paste pressure partially or completely removed, rubber strip 18 takes over

and its initial tension returns the plug 15 to its seat 14 to provide an automatic closing action. The closed position is illustrated in Fig. 4 where a ribbon of tooth paste 25 is shown severed from the tube 10 by the closing action of plug 15 against seat 14 effected by the tension of rubber strip 18. The tooth paste 25 is shown deposited upon the bristles B of a toothbrush T.

It will be observed that the toothpaste 25 has been cleanly severed from the forward or discharge end of the tube 10. To achieve this, the forward enlarged end 16 of the plug 15 is dimensioned to fit the seat 14 so that the closed position of the plug shown in Figs. 1 and 4, the plug 15 is flush with the forward end of the discharge opening 12 which is the seat 14 thereof.

A preferred securement between the plug 15 and the rubber strip 18 is illustrated in Fig. 2 where enlargement 22 at the forward end of rubber strip 18 is laterally slid into the enlargement 26 of the lateral channel 27.

The structure of the plug 16 may be more fully seen in Figs. 5 and 6, where it will be evident that strip 18 can be inserted laterally whereas it will resist longitudinal separation after insertion because enlargement 22 cannot fit through the channel 27.

The illustrated securement is not a limiting feature of the invention but is preferred for economy and ease of manufacture. The strip 18 can be united within plug 15 by making plug 15 of plastic and casting the plastic about the forward end of the strip. Numerous other suitable securements will be obvious to those skilled in the art.

In Fig. 7 as well as in Fig. 1, discharge opening 13 includes a plurality (such as 3 or 4) inwardly directed guide fingers 30 which abut the exterior surface of the plug 15 at spaced points around the circumference thereof intermediate (e.g., midway) the length of the plug. As will be understood abutment or substantial abutment of the fingers 30 with plug 15 occurs when the plug is in the closed position. These guide fingers 30, which may be referred to as pins, are desirably molded integral with the tube 10 and function to hold the conical plug 15 in correct alignment to provide a proper seal with the seat 14. The inclusion of fingers or pins 30 is par-

ticularly preferred when the tube 10 is distorted and the guiding action of the fingers 30 is desirably present to insure a proper seal.

A supplemental closure of conventional type may be used but it is not necessary and if to provide additional protection during long periods of storage prior to sale, may be thrown away by the purchaser.

The invention is defined in the claim which follows.

I claim:

A self-opening and self-closing dispenser for paste-like and semi-solid materials comprising a flexible container formed of thin walled material having a closing crimp at one end and a discharge opening at the opposite end, said discharge opening comprising an outwardly flaring seat, an outwardly tapering conical plug conforming in external dimensions to the inner dimensions of said seat and effective to seal said discharge opening when said plug bears against said seat, the forward end of said plug being enlarged to bring the forward end of said plug flush with the upper surface of said seat when said plug is in closed position in said seat, said plug being provided at its rear portion with a longitudinal channel midway through said plug and extending from an opening at the rear of the plug to the middle of the plug, an enlarged opening at the middle in communication with said channel at the middle of the plug, a tensioned elastic strip secured to the rear end of said tube by said crimp and provided with an enlarged forward end, said strip being dimensioned to slide into said lateral channel and engaging by linking at its enlarged forward end with said enlarged opening and a plurality of circumferentially spaced apart inwardly directed guide fingers positioned in said discharge opening and substantially abutting the exterior surface of said plug intermediate the length thereof when said plug is in its closed position.
